UNITED STATES PATENT OFFICE.

ISADORE DUBERSTEIN, OF LOS ANGELES, CALIFORNIA.

GARMENT HANGER.

Application filed September 21, 1922. Serial No. 589,663.

To all whom it may concern:

Be it known that I, ISADORE DUBERSTEIN, a citizen of the United States, residing at Los Angeles, in the county of Los Angeles and State of California, have invented certain new and useful Improvements in Garment Hangers, of which the following is a specification.

This invention relates in general to improvements in garment hangers, but more specifically it has reference to an attachment adapted to be applied to an ordinary garment hanger and by means of the use of which attachment the efficiency of the hanger will be materially increased.

One of the objects of the invention is to provide an improved hanger particularly adapted though not necessarily limited in its use for supporting dresses, skirts, and the like which are of a flimsy texture and for preventing the dress or garment from dropping off of the hanger in the event that the dress or garment should become accidentally detached from one end of the hanger, and at the same time the attachment is so constructed that it will not injure a dress or garment of the most delicate fibre.

A further object is to provide an improved attachment of this character which will be simple, durable, cheap, and light in construction, effective and efficient in operation, and which may be readily applied to any hanger of this type and as readily removed, and which will not necessitate the employment of fastening or securing devices for maintaining the attachment in position upon the hanger.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which—

Figure 1 is an elevation of a hanger showing the attachment as applied to one end thereof and detached from the other end.

Figure 2 is a view similar to Figure 1, showing the manner in which the attachment operates for sustaining the garment upon the hanger.

Fig. 3 is a side elevation of the hanger showing the manner in which a garment which has been detached from one end will be held from dropping off of the hanger.

Figure 4 is a perspective view of one of the attachments.

The attachment consists of a tubular body portion 10, constructed of any suitable flexible and elastic material, such as rubber or the like and may be of any desired length and of any desired configuration in cross section, but is preferably circular in cross section.

Extending along a portion of the outer surface of the body 10 are a plurality of teeth 11 spaced longitudinally of the body portion and are inclined in a direction toward one end of the body. These teeth 11 are also constructed of elastic material and are preferably constructed of the same material as the body portion 10 and are formed integral therewith.

The hanger 12 to which this attachment is adapted to be applied may also be of any desired configuration but embodies a body portion having connected therewith a suspension hook or device 13, intermediate the ends of the hanger.

In use the attachment is applied by inserting the same over the ends of the body of the hanger 12, the internal diameter of the sleeve forming the body portion of the attachment being preferably of a diameter somewhat less than the external diameter of the body of the hanger 12, so that when the attachment is applied to the hanger the body portion thereof will be expanded and the elasticity of the body will serve to frictionally hold the attachment upon the hanger. This attachment may be spaced for any desired distance from the opposite ends of the hanger but are preferably located in proximity to the end.

The attachments are applied to the opposite ends of the hanger in such a manner that the teeth 11 of each attachment inclines inwardly in a direction towards the center of the hanger and the teeth are of such a height that they will project above the outer surface of the sleeve of the attachment.

When the garment is placed upon the hanger the teeth will not interfere with the garment and inasmuch as the teeth are flex-

ible they will not injure a garment of the finest texture.

Should the garment 14 become detached from one end of the hanger, as shown in Figure 3, the tendency of the garment would ordinarily be to slip from the other end of the hanger and drop to the floor. The flexible teeth 11, however, projecting above the top of the hanger will engage the garment and a frictional gripping will be produced between the teeth and the garment and the garment will be retained upon the hanger.

The spaced teeth 11 present an undulated surface to the garment above the upper face of the hanger body.

The teeth are preferably of a width to extend substantially across the upper surface of the body of the hanger and are preferably substantially parallel, although it is only necessary that the teeth be of such a width as to form a comparatively extended surface to be engaged by the garment, and the height of the teeth increase from one end towards the opposite end of the body portion so as to insure the garment being caught and retained by the remaining teeth if the garment should slip and not be caught by the preceding teeth.

With this improved invention it will be manifest that this attachment may be applied to any hanger of this type and after having been applied will be retained in position by a gripping action caused by the elasticity of the body of the attachment, thereby dispensing with the necessity of providing fastening means for retaining the attachment upon the end of the hanger.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. In combination, a garment hanger embodying a garment supporting bar, and an elastic sleeve adapted to be freely adjusted upon the bar within the confines of the ends of the bar, the internal diameter of the sleeve being less than the external diameter of the bar, said sleeve serving to support and retain the garment upon one end of the hanger when the garment has become detached from the other end of the hanger.

2. In combination, a garment hanger embodying a garment supporting bar, and an elastic sleeve adapted to be freely adjusted upon the bar and within the confines of the extremities of the bar, the internal diameter of the sleeve being less than the external diameter of the bar, said sleeve being provided with a roughened periphery serving to

support and retain the garment upon one end of the hanger when the garment has become detached from the other end of the hanger.

3. In combination, a garment hanger embodying a garment supporting bar, and an elastic open ended tubular member through which the end of the bar is adapted to be passed, said member being freely adjustable upon the bar to any desired distance from the end of the bar, the said member being maintained in its adjusted position upon the bar by friction.

4. In combination, a garment hanger embodying a garment supporting bar, an elastic open ended tubular member through which the end of the bar is adapted to be passed, said member being freely adjustable upon the bar to any desired distance from the end of the bar, the said member being maintained in its adjusted position upon the bar by friction, and upstanding teeth or ribs on the outer periphery of the said member.

5. In combination, a garment hanger embodying a garment supporting bar, an elastic open ended tubular member through which the end of the bar is adapted to be passed, said member being freely adjustable upon the bar to any desired distance from the end of the bar, the said member being maintained in its adjusted position upon the bar by friction, and upstanding teeth or ribs on the outer periphery of the said member, said teeth or ribs inclining in a direction from one end of the member to the other end of the member.

6. In combination, a garment hanger embodying a garment supporting member, a pair of elastic tubular members freely adjustable upon the opposite ends of the hanger member and maintained upon the hanger member entirely by friction, the upper surface of the sleeve being undulated, the said undulations forming pockets into which portions of the garment enter.

7. As an article of manufacture, a garment hanger attachment embodying an open ended elastic tubular body adapted to be sleeved upon the garment supporting bar for suspending the garment, a portion of the outer surface of the body being undulated.

8. As an article of manufacture, a garment hanger attachment embodying an open ended elastic tubular body adapted to be sleeved upon the garment supporting bar to suspend the garment, and a series of teeth projecting above the outer surface of the body.

9. As an article of manufacture, a garment hanger attachment embodying an open ended elastic tubular body adapted to be sleeved upon the garment supporting bar to suspend the garment, and a series of flexible teeth projecting above the outer sur-

face of the body, the teeth increasing in height from one end towards the other end of the body.

10. As an article of manufacture, a garment hanger attachment embodying an elastic tubular body adapted to be sleeved upon the hanger, and a series of flexible teeth projecting above the outer surface of the

body, the said teeth inclining in a direction towards one end of the body portion and 10 successively increasing in height from one end of the body.

In testimony whereof I have signed my name to this specification on this 18th day of September, A. D. 1922.

ISADORE DUBERSTEIN.
